UNITED STATES PATENT OFFICE.

GEORGE MILLER, OF BALTIMORE, MARYLAND.

CALCIUM-CARBID HOLDER.

SPECIFICATION forming part of Letters Patent No. 635,865, dated October 31, 1899.

Application filed August 31, 1899. Serial No. 729,035. (No model.)

To all whom it may concern:

Be it known that I, GEORGE MILLER, a resident of Baltimore, in the State of Maryland, have invented certain new and useful Improvements in Calcium-Carbide Holders; and I do hereby declare the following to be a full, clear, and exact description of the invention, such as will enable others skilled in the art to which it appertains to make and use the same.

10 My invention relates to an improvement in calcium-carbide holders, and more particularly to a cartridge for acetylene-gas lamps, the object of the invention being to provide a device of the above-mentioned character which

15 will be extremely simple in construction, neat in appearance, effectually exclude air and moisture, and which shall be most convenient for use.

With this object in view the invention consists in certain novel features of construction and combinations and arrangements of parts, as will be more fully hereinafter described, and pointed out in the claims.

In the accompanying drawings, Figure 1 is a view in longitudinal section illustrating my improvements. Fig. 2 is an end view, and Fig. 3 is a view of a modification.

Heretofore in the manufacture of calcium-carbide cartridges a metal receptacle has been provided with an opening in each end covered by tin-foil or other material to prevent the admission of moisture when not in use and permit the ready insertion of a tube or other device to admit the water to the carbide and permit the escape of gas. One way of fastening this covering over the opening has been to solder it to the receptacle; but this and all other means now in use have proven not only tedious and expensive, but have resulted in 30 making the cartridge very unsightly; and it is the object of my invention to so construct the cartridge that the covering will be secured to the receptacle while the can is being manufactured, thus resulting in an extremely slight expense and at the same time give to the cartridge a neat and attractive appearance, besides making the cartridge much stronger and more durable than those now in use.

A represents a cylindrical body provided at each end with an outwardly-flaring flange 1, and B represents the ends of the cartridge,

each having a central opening 2 therein. The ends B are provided with flanges 3, bent first upwardly and then downwardly to inclose the upper and lower flanges, respectively, of the 55 body and to clamp disks 4, of tin-foil or other suitable material easily punctured, similar in general shape to the said ends B. It will thus be seen that one end of the can, with the tin-foil disk, can be placed on the body before the 60 calcium carbide is placed in the cartridge, and after the cartridge is charged the other end and tin-foil disk can be readily secured in place.

In the form of the invention shown in Fig. 65 3 the ends of the body portion A of the can are made slightly flaring, as shown at 5, and the heads B' (each provided with a central hole 6) are made flat and their peripheries are bent to embrace the flaring ends of the body 70 portion, the tin-foil disks being secured in place in the manner hereinbefore described.

Various slight changes might be resorted to in the general form and arrangement of the several parts described without departing 75 from the spirit and scope of my invention, and hence I would have it understood that I do not wish to limit myself to the precise details set forth, but consider myself at liberty to make such slight changes and alterations 80 as fairly fall within the spirit and scope of my invention.

Having fully described my invention, what I claim as new, and desire to secure by Letters Patent, is—

1. As an article of manufacture, a calcium-carbide holder comprising a body open at each end, ends for said body having openings therein, a covering for each end of material easily punctured and adapted to close said openings, 90 said ends secured at their edges to the body with the edges of the covering between them and the ends of the body.

2. As an article of manufacture, a calcium-carbide holder comprising a cylindrical body 95 having its ends made flaring, ends for said body having openings therein, of material easily punctured adapted to cover said openings in the ends and flanges on said ends adapted to clamp the flaring ends of said body and 100 secure the coverings in place.

3. A carbide-cartridge consisting of a body

portion, ends therefor, each having a hole, tin-
foil disks covering the holes in said ends and
overlapping the ends of the body portion and
flanges on said ends embracing the ends of
5 the body portion and the ends of said tin-foil
disks.

In testimony whereof I have signed this

specification in the presence of two subscriv-
ing witnesses.

GEORGE MILLER.
